UNITED STATES PATENT OFFICE.

ALBERT H. SNAPP, OF CHICAGO, ILLINOIS.

DESIGN FOR A FLOWER-POT.

SPECIFICATION forming part of Design No. 24,109, dated March 12, 1895.

Application filed January 2, 1895. Serial No. 533,637. Term of patent 7 years.

To all whom it may concern:

Be it known that I, ALBERT H. SNAPP, a citizen of the United States of America, residing at Chicago, in the county of Cook and State of Illinois, have invented a new and original Design for Flower-Pots, of which the following is a specification.

My invention relates to a new and original design for flower pots, of which the following is a description.

The drawings presented herewith show a perspective of my design in Figure 1; and a vertical diametrical section in Fig. 2.

Looking at the drawings the design is seen to consist of a substantially cylindrical outer portion, A, having a flat bottom, a rounded lower margin and a number of feet, B; and

provided with an inner portion, C, substantially conforming to the interior of the outer in shape, but curved outward at the top in the form of an annular flange, c, with rounded outward edge.

The essential features of my design I consider to be the cylindrical shape of the flower pot together with the outwardly turned upper horizontal flange, c.

I claim as new and desire to secure by Letters Patent—

The design for a flower pot herein shown and described.

ALBERT H. SNAPP.
